UNITED STATES PATENT OFFICE.

JOHN RANK AND HENRY W. RANK, OF MINNEAPOLIS, MINNESOTA.

TRAFFIC SIGNAL.

Application filed September 3, 1925. Serial No. 54,240

Our invention relates to traffic signals of the post type that are adapted to be rigidly set in the street and which are adapted to resist normal stress without bending but which, 5 if struck by a vehicle, will deform and readily yield and move into an approximately horizontal position but will resume their direct or operative position when released from the engaging vehicle without vibration. Such 10 traffic signals, broadly considered, have hitherto been proposed and produced, but they have either been ineffective or otherwise unsatisfactory in action or have been complicated and expensive in construction. The 15 chief object of this invention is the provision of a highly efficient and reliable traffic signal embodying the characteristics above noted and which is of simple construction, relatively low cost, not likely to get out of order or be 20 damaged by a vehicle passing over the same due to its low resistance to bending when deformed, and which will be sure to resume its erect or operative position when released without vibrating; and, to the above ends, 25 generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view chiefly in elevation, but with some parts in vertical section, showing a 35 traffic signal embodying our invention and the deformation of the post section in bending:

Fig. 2 is a fragmentary view in vertical section on the line 2—2 of Fig. 1, some parts 40 being shown in full;

Fig. 3 is a fragmentary section taken on the line 3—3 of Fig. 1;

Fig. 4 is a detail in horizontal section, on the line 4—4 of Fig. 1;

Fig. 5 is a detail in plan, showing a lower spacing head or bushing placed in the casing or rigid body portion of the signal device;

Fig. 6 is a bottom plan view of the cap plug of the casing;

Fig. 7 is a section on the line 7—7 of Fig. 3 showing the normal cross-sectional area of the deformable post section;

Fig. 7^a is a view corresponding to Fig. 7, but illustrating a slightly modified wall structure; and

Fig. 8 is a view in elevation, illustrating a

somewhat modified form of the signal device.

The construction illustrated in Figs. 1 to 7, inclusive, will first be described. In this structure, the signal device is in the nature of a flexible post made up of a rigid casing or section, a base plug or section, and a flexible tubular section connecting the casing and base plug. The flexible permanently integral, tubular post section employed in this signal or indicating device is relatively inelastic longitudinally and of such normal cross-sectional area as to resist normal stress (such as a person leaning against the post, high wind pressure, etc.) without bending but which is designed to readily bend under pressures even less than such normal stress to which these posts are subjected when deformed by impact of a heavy vehicle. It will be seen that when a post, made in accordance with this invention, is thus formed that it will bend with decreasing resistance to stress as the cross-sectional area of the post is reduced at the point of bending, as it approaches an approximately horizontal position and when released will return to erect position without vibration. The casing in this particular structure is made up of four flat plates 9, preferably of sheet metal, in rectangular arrangement and having outturned flanges that are, by nut-equipped bolts 10, clamped onto corner strips 11 of rubber, wood or other suitable substance, which causes said strips to act as buffers or shock-reducing devices. Telescoped into the lower end of the casing made up of the plates 9 is a rectangular head 12 rigidly secured to the said plates, preferably by machine screws 13. This head 12 has a large internally threaded opening 14. The upper end of the casing, as shown, is closed 95 by a head or cap 15 having a square shank 16 telescoped into said casing and rigidly secured thereto by screws 17 or other suitable devices.

The lower post section or plug 18 must be 100 anchored to a suitable base in the road bed and, as shown, said member has a threaded shank 19 screwed into a base plate 20, which, in turn, is anchored to a concrete base 21 by nut-equipped anchor bolts 22. The concrete 105 base 21 is set into or constitutes part of the road bed.

The flexible or deformable tubular member 23 is preferably made up of alternated layers of rubber and canvas built up much on the 110 plan of the outer casing of an automobile tire but of complete cylindrical form to per-

mit flexing but resisting longitudinal stretching. In Fig. 7, said tube is shown as made up of outer and inner layers of canvas 23^a and an interposed layer of rubber 23^b, while in Fig. 7^a, said tube is shown as made up of outer and inner layers of rubber 23^b and an interposed layer of canvas 23^a. In Fig. 3, the numeral 23^c indicates a coiled metal spring imbedded in the intermediate rubber layer 23^b. From what has just been said, it will be understood that this flexible rubber tubular post may be built up or made in various different ways.

The said flexible tube 23^a constitutes a normally rigid but yielding connection between the base member and the casing of the signal post or indicating device and, preferably, the said connections are made as follows: Telescoped into the upper end of the flexible tube 23 is a coupling tube or tubular nipple 25. Surrounding the upper end of said tube 23 is a clamping band 26, and passed through said clamping band, the upper end of said tube 23, and the lower portion of the coupling tube 25, are nut-equipped bolts 27. The upper end of the coupling tube 25 is threaded and is screwed into the threaded opening 14 of the spacing head 12.

The lower post section or plug 18 is also 30 tubular, much like the coupling tube 25, and the lower end of the flexible tube 23 is telescoped onto the upper end of said lower section 18. The lower end of the tube 23 is rigidly but detachably secured to the tubular section 18 preferably by substantially the same means used to connect the upper end of said tube 23 to the coupling tube 25 and, hence, it is only desirable here to note the lower clamping ring 28 and nut-equipped bolts 29.

It is evident that the post constructed as described will stand in normally rigid upright or true vertical position, resisting bending under normal stress but that, if struck 45 by an automobile or other vehicle, the tube 23 will be deformed and will then readily yield permitting the post to be bent into a horizontal position without breaking of the post and without serious damage to the post. Of course, under very violent impacts, even a yielding post may sometimes be damaged, but the post will seldom be damaged to a serious extent and, at any rate, will not seriously damage the automobile striking the same and will not endanger the lives of persons in the machine. Of course, when released, the deformed flexible tube 23 will instantly throw the post back to its erect or operative position without vibration. The 50 buffer or cushion strips 11, at the corners of the casing, will reduce to a minimum the impact and lessen the liability of damage to the signal device when struck by an automobile or vehicle.

65 The post just described is especially de-

signed for use in connection with illuminated "Stop" and "Go" signals exposed through letters applied in the plates 9 or in the sides of the casing. For such "Stop" and "Go" signals, light bulbs will be placed within the 70 casing and wires will be extended thereto from a suitable source of supply and through suitable controlling switches, which, however, per se, constitute no part of the present invention and may be such as hitherto employed and quite generally known. The control wires in this arrangement are adapted to be passed through the tubular members 18 and 25 and may be brought out from the cavity 21^a of the concrete base 21 through a lead 80 passage 21^b. Obviously, the flexible tube 23 affords an ideal housing for the wires thus brought into the casing, for such wires will readily follow the bend of the tube when the signal post is forced into a horizontal position, and there will be no short kinking of the wires.

The signal device or post illustrated in Fig. 8 differs from that illustrated in Figs. 1 to 7, in that the upper or rigid casing is in 90 the form of a metal tube or cylinder 30 provided with circumferentially spaced light passages 31. The manner of connecting the members of this post may be the same as that illustrated in the views before described, the 95 only difference being that the head inserted into the lower end of the tubular casing 30 will have a cylindrical exterior instead of the rectangular exterior of the head 12, shown in detail in Fig. 5. The signal device or post 100 shown in Fig. 8 is of the kind used, not to flash "Stop" and "Go" signals, but simply to afford a warning signal or indicator at crossings.

The simplicity of the construction described is obvious. Not only is the device simple, but highly efficient. No springs or complicated arrangement of mechanism are required. The device may, therefore, be manufactured at comparatively low cost and 110 quickly and easily installed.

What we claim is:

1. A traffic signal in the form of a post and comprising an anchoring base, a hollow rigid upper section having sign-bearing elements, 115 and a resilient integral tubular section deformable in cross-section and connected to said anchoring base and said rigid upper section and adapting the latter to be readily turned from a normal upright position into 120 an approximately horizontal position when the tubular section is deformed.

2. A traffic signal in the form of a post and comprising an anchoring base, a hollow rigid upper section having sign-bearing elements, and a resilient integral tubular section of fabric reinforced rubber connected to 125 said anchoring base and said rigid upper section and adapting the latter to be readily turned from a normal upright position into 130

an approximately horizontal position when the tubular section is deformed.

3. A traffic signal in the form of a post and comprising an anchoring base, a hollow rigid upper section having sign-bearing elements, and a resilient integral tubular section connected to said anchoring base and said rigid upper section and adapting the latter to be turned from a normal upright position into an approximately horizontal position, said rigid upper section being rectangular in cross section and provided at its corners with projecting buffers.
4. A non-vibrating self-aligning street traffic indicator in the form of a post, comprising a resilient post member deformable in cross-section and having a rigid anchoring base, said post member being of such cross-sectional area as to resist normal stress without bending but bendable under reduced stress when deformed.

5. A non-vibrating, self-aligning street traffic indicator in the form of a post, comprising a resilient tubular post member deformable in cross-section and having a rigid anchoring base, said post member being of such normal cross-sectional areas as to resist bending under normal stress and readily bendable where the cross-sectional area is reduced when deformed under abnormal stress.
6. A non-vibrating, self-aligning traffic signal in the form of a post having a rigid anchoring base and a signal bearing upper section, and a permanently integral resilient tubular intermediate section secured to said anchoring base and providing a normally rigid support for said upper section, said tubular section being of such normal cross-sectional area as to resist bending under nor-

mal stress and capable of flattening in bending intermediate its ends under abnormal stress, whereby resistance to bending decreases in proportion to the decrease in cross-sectional area at the point of flattening.

7. A bendable self-aligning street traffic indicator in the form of a post, comprising a rigid anchoring base, and a resilient transversely deformable post section secured to said base, said post section being relatively inelastic longitudinally and of such cross-sectional area as to resist normal stress without bending but bendable under reduced stress when deformed.

8. A bendable self-aligning street traffic indicator in the form of a vertical post, comprising a flexible permanently integral tubular member deformable in cross-section and having a rigid anchoring connection with the ground, said tubular member being of such cross-sectional area as to be substantially rigid under normal stresses but bendable under stress equal to normal stresses when deformed.

9. A bendable self-aligning street traffic indicator in the form of a vertical post, comprising a flexible permanently integral tubular post member anchored at one end to the ground and of such cross-sectional area as to be substantially rigid until subjected to such stress as would cause the wall of said tubular post member to deform permitting bending of the post at the point of deformation with materially less stress than is required to deform the post wall.

In testimony whereof we affix our signatures.
